UNITED STATES PATENT OFFICE.

MORRIS THOMPSON, OF NYACK, NEW YORK.

TIRE PROTECTOR.

Application filed March 8, 1923. Serial No. 623,726.

To all whom it may concern:

Be it known that I, MORRIS THOMPSON, a citizen of the United States, residing at Nyack, in the county of Rockland and State 5 of New York, have invented certain new and useful Improvements in Tire Protectors; and I do hereby declare the following to be a full, clear, and exact description of the invention, such as will enable others 10 skilled in the art to which it appertains to make and use the same.

The invention has relation to protective means for pneumatic tires, whereby to prevent puncture or blowout, said protector 15 being of unbroken circular form and transversely curved to conform with the size of tire for which it is designed. The protector is preferably constructed from steel, although any material suitable for the purpose 20 may be employed, and the protector may be plain or lined and may be placed within the casing so as to come between the inner tube and shoe, or may be disposed upon the outer side of the shoe, or built or 25 incorporated therein as a part thereof, and is provided with spurs which may form a part thereof or be applied thereto, said spurs operating to prevent slipping and guard against skidding. When a protector 30 of this type is located within the shoe, the spurs penetrate the latter and protrude beyond the outer surface thereof.

Other objects and advantages will be apparent and suggest themselves as the nature 35 of the invention is understood.

While the drawings illustrate an embodiment of the invention it is to be understood that in adapting the same to meet different conditions and requirements, various changes 40 in the form, proportion and minor details of construction may be resorted to without departing from the nature of the invention.

Referring to the accompanying drawings forming a part of the application;

Figure 1 is a sectional view of a protector embodying the invention,

Figure 2 shows the protector incorporated in the casing as a part thereof,

Figure 3 is a detail view showing the protector disposed between the inner tube and casing, the spurs projecting through the latter,

Figure 4 is a side view of a portion of the protector, and

Figure 5 is a view similar to Figure 1, 55 showing a lining applied to the inner side of the protector.

Corresponding and like parts are referred to in the following description and designated in the several views of the drawings by like reference characters.

The numeral 1 designates the protector which, in practice, is of annular form and transversely curved, it being understood that the protector will be provided in different 65 sizes to adapt the same to the various sizes of tires. Opposite edge portions of the protector are outwardly beveled to prevent the formation of inner corners and to enable the same to obtain a close fit in the several 70 adaptations of the invention. It is preferred to construct the protector of steel, although any material suitable for the purpose may be employed. The protector may be placed against the inner or the outer side 75 of the casing, or may be built therein as a part thereof, as indicated most clearly in Figure 2. If preferred, a suitable lining 3 may be applied to the inner side of the protector to come between it and the inner tube 4 80 and prevent possible injury to the latter. The protector 1 is provided with spurs 5 which may form a part thereof or be applied thereto in any manner. These spurs prevent slipping and skidding and, as stated, 85 the protector may be applied either to the inner or the outer side of the casing, or built in as a part thereof. Figure 3 shows the protector disposed between the casing 6 and the inner tube 4 with the spurs 5 projecting through the casing.

What is claimed is:

A tire protector consisting of an annular metallic band arcuate in cross section, spurs on said band and adapted to project through 95 and beyond a tire casing and be disposed in the casing substantially throughout the length of the spurs, the side edges of the band being substantially feathered, and a lining on the inner surface of the band. 100

In testimony whereof I affix my signature in presence of two witnesses.

MORRIS THOMPSON.

Witnesses:

HELEN THOMPSON,
Wm. P. BUGBEE,
